US00D785810S

(12) **United States Design Patent** (10) Patent No.: **US D785,810 S**
(45) Date of Patent: ** May 2, 2017

(54) **TWO COMPONENT MIXING TIP**

(71) Applicants: **Daniel Wang**, Rowland Heights, CA (US); **Bo Tao**, Chino, CA (US); **Xiao Yang**, Walnut, CA (US)

(72) Inventors: **Daniel Wang**, Rowland Heights, CA (US); **Bo Tao**, Chino, CA (US); **Xiao Yang**, Walnut, CA (US)

(73) Assignee: **PAC-DENT INTERNATIONAL, INC.**, Brea, CA (US)

(**) Term: **15 Years**

(21) Appl. No.: **29/544,452**

(22) Filed: **Nov. 3, 2015**

(51) LOC (10) Cl. **24-00**

(52) U.S. Cl.

USPC **D24/220**

(58) **Field of Classification Search**

USPC D24/220, 231; D15/138; D9/447

CPC A61C 9/0026

See application file for complete search history.
